UNITED STATES PATENT OFFICE.

NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA.

WALL-BED PIVOT MOUNTING.

Application filed December 22, 1926. Serial No. 156,811.

This invention relates to wall beds of the revolving vertically pivoted type and has to do with specific pivotal mounting of the bed frame.

5 The objects of the invention are to provide an improved pivotal mounting of the bed frame in which, while the vertical pivots are considerably to one side of the vertical center of the bed frame yet the bed frame itself is 10 supported in its center, also such a mounting which is preferably independent of the door, but is adapted to easy attachment or detachment of a door without disturbing the mounting elements, also such a construction which 15 will provide for quick installation and alignment of the members to insure free running, and withal such a construction which will be cheap and simple to construct and neat in appearance.

20 The drawings accompanying this application show my preferred embodiment of the invention, Fig. 1 being a vertical view in perspective of the complete mounting elements with the head frame of a metal bed secured in 25 position, while Fig. 2 is a side elevation of the mounting showing it in place between the floor of a room and the head jamb of a doorway.

In the drawings the head frame of a bed 30 is designated 1 and is shown secured to a vertical pipe bar 2.

This bar 2 stands in the vertical center of the frame 1 and is bolted thereto at 3 and secured by means of a bracket at 4, while above 35 and below these points the pipe bar is bent at right angles through gentle curves so as to lie parallel to the plane of the head frame and at the end the pipe bar is secured to upper and lower brackets 5 and 6 respectively by 40 means of bolts 7 and 8 passing through slots 9 and 10 in the plates respectively and directly through the pipe, a spacing or seating washer as at 11 preferably being positioned between the pipe and the bracket.

45 Bracket 5 comprises an inverted L shaped plate with a pivot hole at 12 in the short leg adapted to receive the vertical downwardly extending pivot 13 secured to plate 14 which is adapted for securing to the head jamb 15 50 or upper lintel of a door frame as shown in Fig. 2.

Bracket 6 comprises a Z shaped plate with its lower leg apertured to receive a vertical upwardly extending pivot 16 secured to a 55 plate 17 adapted for securing to the floor 18

or lower door jamb as indicated in Fig. 2 so as to bring the pivots 13 and 16 in vertical alignment.

This plate 17 it should be noted has a projection or lug 17' on one edge from which the 60 pin 16 extends and this is important in avoiding an unsightly plate from showing below the door.

When in position the bed frame 1 will be seen to be rigidly supported on a central vertical bar 2 swingable about vertical pivots 13 and 16 aligned on an axis as dotted at 19 passing vertically at a distance from one end of the head frame equal to about a quarter of its width, or that is, laterally offset from 70 the vertical center line of the head frame about a quarter or third of its width, but still in a plane parallel with the plane of the frame.

In practice a washer is placed on the pivot 75 under the lower bracket plate 6 to take the weight of the bed as indicated at 23 in Fig. 2.

The plates 5 and 6 present forwardly flat aligned surfaces against which a door 20 or other panel is adapted to be placed with its 80 lower edge notched and resting on the outwardly turned flange of the Z plate and the panel secured in position by screws passing through the holes in the plates shown.

The lower rail 1' of the head frame of the 85 bed is in the showing made of an angle iron and it rests upon the upper flange of the Z plate 6 and is secured thereto by a bolt 21 passing through a slot 22 in the plate.

By the structure described the vertical bar 90 with laterally offset ends forms a species of U or Z bar rigidly secured to the head frame of the bed and to the pivot brackets, and the slots and connections shown provide for quick adjustment for desired clearances and 95 alignment, and placing or removal of the door without disturbing the mounting.

It should be understood that the I only 100 show the head frame 1 of the bed in position, that this frame pivotally carries the main body of the bed, not shown, on lower brackets 24 so that it may be swung to vertical position or lowered to horizontal extension from the head frame in the well known manner common to vertically pivoted wall beds but 105 this all being ulterior to the invention in question has been omitted from this case.

In operation the bed with or without a door in place on the brackets may be revolved about the vertical pivots to throw the bed 110

to either side of the wall 25 for letting down to sleeping position, and the offset arms of the U bar may be given any length desired so as to effect an equal offsetting or lateral 5 displacing of the bed relative to the vertical pivot axes when the bed is swung from one side of the wall to the other, and also the bracket arrangement permits of any width of door being quickly mounted thereon or 10 with any desired offset relation to the bed itself, thus adapting the mounting to a variety of conditions commonly met with in bed installations.

I claim:

- 15 1. A mounting for a wall bed of the vertically pivoted type including an end frame of a bed, a vertically disposed bar secured on its vertical run to said end frame, offset ends on said bar extending parallel to the 20 plane of the frame, brackets vertically slotted and secured therethrough to said ends

whereby the brackets are vertically adjustable on said bar, vertical pivot joints on said brackets, and said frame also secured to one of said brackets through a slot in the same 25 whereby the plane of the frame may be adjusted with respect to the vertical.

2. Amounting for a wall bed of the vertically pivoted type including an end frame of a bed, a vertically disposed bar rigidly 30 secured on its vertical run to said end frame, offset ends on said bar extending parallel to the plane of the frame, brackets secured to said ends, vertical pivotal joints on said brackets, and said frame also secured to the 35 lower of said brackets, means for adjusting said bar vertically with respect to said brackets, and means for adjusting the frame horizontally on the lower one of said brackets.

NEIL SINCLAIR.
